PICTURE WINDOW CONSTRUCTION

Fred O. Oerly, Booneville, Mo., assignor of one-half to
Harland R. Stretz, Booneville, Mo.

Application August 26, 1957, Serial No. 680,108

5 Claims. (Cl. 20—56.1)

This invention relates to building structure and, more particularly, to window construction which includes pane structure tiltable within its frame to various positions depending upon seasonal variations in the weather.

The most important object of this invention is to provide picture window construction wherein the pane structure within the frame may be tilted from an outer vertical winter position to an inwardly tilted summer position to thereby change the angle of reflection of the pane with respect to outside light and permit a greater amount of light to enter the building during winter months, while reflecting a greater proportion of light rays away from the building during summer months.

Another important object of this invention is to provide picture window construction as described wherein the lowermost edge of the pane structure is shiftable horizontally so that the relative angularity of the pane with respect to a vertical reference plane may be changed to cause a greater proportion of light rays to be reflected from the pane before the same enter the building during summer months, than during winter months when the pane structure is disposed in a substantially vertical position.

Also an important object of this invention is to provide window construction wherein potted plants or the like may be disposed at the lowermost portion of the shiftable pane structure so as to be located within the building on the inside of the pane during winter months and which will be disposed without the building on the outside of the pane upon shifting of the latter to a winter position.

Other important objects of the invention relate to a frame for receiving a shiftable pane wherein there are provided a pair of horizontally spaced grooves alternately receiving the lowermost edge of the pane so that the same may be shifted to alternate winter and summer positions with the pane being tilted downwardly during winter months; to the provision of a frame wherein grooves are utilized to receive the edges of the pane to thereby preclude the necessity of hinge mechanisms or the like; to the provision of triangularly shaped cutouts in the sides of the frame receiving the pane structure to limit the extent of shifting movement of the pane structure to a path of travel between the grooves alternately receiving the lowermost edge thereof, thereby preventing dislodgement of the pane structure from its frame; to triangular inserts which may be positioned within the cutouts to support the upright marginal portions of the pane structure when the same is disposed in one of its positions and which inserts may be readily shifted to the other side of the pane when the latter is moved to another one of its positions; and to other lesser important objects and details of construction which will become obvious as the following specification progresses.

In the drawing:

Figure 1 is a perspective view of picture window construction embodying the concepts of the present invention,

2

certain of the parts being broken away to reveal details of construction;

Fig. 1 is an enlarged, vertical, cross-sectional view of the construction shown in Fig. 1 and illustrating the pane structure in one of its positions;

Fig. 3 is an enlarged, vertical, cross-sectional view similar to the one illustrated in Fig. 2 and showing the pane structure in another of its positions; and

Fig. 4 is a fragmentary, further enlarged horizontal, cross-sectional view taken on the line IV—IV of Fig. 2 and looking in the direction of the arrows.

Adjustable picture window construction as contemplated by this invention is designated generally by the numeral 10 and as preferred components thereof includes a rectangular frame 12 having a pair of spaced, opposed upper and lower members 14 and 16 and side elements 18. Shiftably mounted within frame 12 is pane structure designated generally 20 and which includes a rectangular pane 22 and spaced, opposed upper and lower edge components 24 and 26 respectively and side marginal components 28.

As is clearly shown in Figs. 2 and 3, member 14 is provided with a longitudinally extending groove 30 therein located adjacent the normally outermost face 32 of frame 12, while member 16 is provided with a pair of horizontally spaced grooves 34 and 36, groove 34 being located adjacent face 32 of frame 12 and lying in a common vertical plane with groove 30, whereas groove 36 is disposed adjacent normally innermost face 38 of frame 12. Grooves 30, 34 and 36 are of sufficient width to receive the edge components 24 and 26 respectively of pane structure 20 and, as apparent from Figs. 2 and 3, grooves 34 and 36 alternately receive edge component 26 of structure 20. The distance between the remotest portions of opposed grooves 30 and 34 as well as groove 36 is greater than the distance between the edges of components 24 and 26 for reasons to be hereinafter outlined.

Each of the side elements 18 is provided with inwardly facing, opposed triangularly shaped cutouts 40 which are adapted to receive corresponding side marginal components 28, it being noted that the uppermost apex of each of the triangular cutouts 40 merge with respective ends of groove 30. Furthermore, the base of cutout 40 is substantially equal in length to the distance between grooves 34 and 36.

A triangular insert 42 is located within each of the cutouts 40 and is removably held in position therein by suitable screw means 44. As shown in Figs. 2 and 3, each of the triangular inserts 42 is constructed so as to present a right angle at the base thereof and make the same reversible when pane structure 20 is shifted within frame 12.

Each of the grooves 30, 34 and 36 respectively is provided with resilient gasket means 46 so as to render the pane structure weather-tight at the upper and lower edges thereof, and additional resilient gasket material 48 is provided on the vertical marginal edges of sides 18 defining corresponding cutouts 40 to provide a seal when marginal components 28 are disposed against the same.

The member 16 is provided with a longitudinally extending depression 50 formed therein of sufficient dimensions to accommodate flower pots 52 or the like, and it is noted that such pots 52 may be supported by structure 54 of building wall 56.

From the foregoing description it can now be understood that pane structure 20 is shiftable from a substantially vertical winter position illustrated in Fig. 2 to a tilted location during summer months, which is illustrated in Fig. 3. The upper edge component 24 of pane structure 20 is slidably and pivotally disposed with

in groove 30 and, inasmuch as the distance between the remotest opposed portions of grooves 30 and 34 or 36 is greater than the distance between upper and lower edge components 24 and 26 respectively of pane structure 20, the latter may be shifted from the position illustrated in Fig. 2 to that of Fig. 3, or vice versa, by merely moving structure 20 upwardly in groove 30 until the lowermost part of component 26 clears member 16, whereupon component 26 may be shifted horizontally to another one of the grooves 34 or 36.

After the pane structure 20 has been shifted to a position with lower component 26 disposed in one of the grooves 34 or 36, the triangular inserts 42 may be inserted in corresponding cutouts 40 to provide support for marginal components 28. By virtue of the configuration of inserts 42, the same are adapted to be utilized in supporting relationship to marginal components 28, irrespective of the angular disposition of pane structure 20, and it can be appreciated that by merely turning inserts 40 one hundred-eighty degrees, the same may be fitted into cutouts 40 in supporting relationship to respective marginal components 28. The screw means 44 with which triangular inserts 42 are secured to respective elements 18 may be quickly and easily removed when it is desired to shift pane structure 20 to another one of its positions.

Since pane structure 20 is normally disposed in the vertical position of Fig. 2 during winter months, a greater proportion of light rays are permitted to enter pane 22, inasmuch as there will not be as great a degree of reflection of light while pane 22 is located in such vertical position, and also, flowers or the like within pots 52 will be disposed within the building and on the inside of pane structure 20 and thus will not be subjected to freezing weather conditions or the like. Furthermore, because of the disposition of pots 52 adjacent pane 22, light rays may readily pass through pane 22 and onto flowers or the like within pots 52 to assure that the plants receive sufficient sunlight.

However, when pane structure 20 is shifted to the position illustrated in Fig. 3, a greater proportion of light rays are reflected from pane 22 downwardly than is the case when structure 20 is disposed in a vertical position and thus, the area within the building is maintained at a lower temperature. Also, light being deflected from the downwardly tilted surface of pane 22 is directed onto the plants within pots 52 to thereby facilitate growth of the same.

Having thus described the invention what is claimed as new and desired to be secured by Letters Patent is:

1. In window construction, a frame provided with a pair of horizontal, vertically spaced, opposed members; and pane structure mounted in said frame and having upper and lower opposed edges, one of said members being provided with means pivotally and slidably receiving said upper edge of the structure and the other member having horizontally spaced means therein for alternately receiving the lower edge of the structure in any one of a plurality of preselected, spaced positions whereby the relative angularity of the structure with respect to a reference point may be changed.

2. In window construction, a frame provided with a pair of horizontal, vertically spaced, opposed members; and pane structure mounted in said frame and having

upper and lower opposed edges, the upper member being provided with a downwardly facing groove slidably and pivotally receiving said upper edge of the structure and the other member having a pair of horizontally spaced upwardly facing grooves therein alternately receiving said lower edge of the structure whereby the relative angularity of the structure with respect to a reference point may be changed.

3. In window construction, a rectangular frame provided with pairs of opposed members and elements; and rectangular pane structure mounted in said frame and having pairs of opposed edges and margins, one of said members being provided with a groove slidably and pivotally receiving one of said edges of the structure, the other member having a pair of spaced grooves therein alternately receiving the other edge of the structure whereby the relative angularity of the structure with respect to a reference point may be changed and said element being provided with triangularly shaped cutouts receiving said margins of the structure for limiting the extent of shifting of said other edge of the structure to a path of travel between said spaced grooves in said other member.

4. In window construction, an upright rectangular frame provided with pairs of opposed members and elements; rectangular pane structure mounted in said frame and having pairs of opposed edges and margins, one of said members being provided with a groove slidably and pivotally receiving one of said edges of the structure, the other member having a pair of horizontally spaced grooves therein alternately receiving the other edge of the structure whereby the relative angularity of the structure with respect to a reference point may be changed, the distance between the remotest portions of the grooves in opposed members being greater than the distance between said edges of the structure and said element being provided with triangularly shaped cutouts receiving said margins of the structure for limiting the extent of shifting of said other edge of the structure to a path of travel between said spaced grooves in said other member; and triangular inserts removably mounted in each of said cutouts for supporting corresponding margins of the structure when the said other edge of the structure is disposed in one of the grooves in said other member.

5. In window construction, an upright rectangular frame provided with opposed upper and lower members and side elements; and rectangular pane structure mounted in said frame and having opposed upper and lower edges and side margins, said upper member being provided with a groove slidably and pivotally receiving said upper edge of the structure, the lower member having a pair of horizontally spaced grooves alternately receiving said lower edge of the structure whereby the relative angularity of the structure with respect to a vertical reference plane may be changed, said lower member being provided with an article-receiving depression positioned between said grooves therein whereby articles in said depression will be alternately disposed on opposed sides of said pane structure as the latter is shifted.
